DESIGN FOR A RAZOR BLADE SHARPENER FOR PENCILS

Eugene Weiss, Los Angeles, Calif.

Application January 18, 1945, Serial No. 117,497

Term of patent 7 years

(Cl. D74—1)

To all whom it may concern:

Be it known that I, Eugene Weiss, a citizen of the United States, residing at Los Angeles, California, in the county of Los Angeles and State of California, have invented a new, original, and ornamental Design for a Razor Blade Sharpener for Pencils, of which the following is a specification, reference being had to the accompanying drawing, forming a part thereof.

In the drawing:

Fig. 1 is a perspective view of a razor blade sharpener for pencils, showing my new design;

Fig. 2 is a rear perspective view;
Fig. 3 is a bottom view;
Fig. 4 is a vertical sectional view taken on the line 4—4 of Fig. 3; and
Fig. 5 is a vertical sectional view taken on the line 5—5 of Fig. 3.

I claim:

The ornamental design for a razor blade sharpener for pencils, as shown.

EUGENE WEISS.
